UNITED STATES PATENT OFFICE.

BYRON B. GOLDSMITH, OF NEW YORK, N. Y.

FINGER-HOLD FOR PENHOLDERS.

SPECIFICATION forming part of Letters Patent No. 768,985, dated August 30, 1904.

Application filed January 19, 1904. Serial No. 189,683. (No model.)

To all whom it may concern:

Be it known that I, BYRON B. GOLDSMITH, a citizen of the United States, residing in the city and State of New York, have invented a new and useful Improvement in Finger-Holds for Penholders, of which the following is a specification.

The object of my invention is to provide a finger-hold for penholders which shall be easy of construction and which will yet present an elastic and yielding mass to the finger-tips of the writer, so that the penholder may be securely grasped with little effort, an increased degree of elasticity and smoothness being given to the writing, and writer's cramp be avoided.

It has heretofore been proposed with a view of attaining the objects at which I aim to construct finger-holds for penholders of cork; but these have been found unsatisfactory by reason of their comparatively unyielding character. It has also been proposed to build the finger-hold of soft rubber. Now a finger-hold of a solid cylinder of soft rubber without any core of rigid material on the inside is impracticable, since it wobbles in writing. It has therefore been proposed to build penholders with a solid core or ferrule, which supports and prevents the wobbling of the pen, and to surround this core or ferrule with a soft-rubber sleeve in the form of a tube. Since, however, the body of the surrounding soft-rubber sleeve could have no great thickness in a radial direction and since soft rubber at best is not very elastic, such soft-rubber finger-holds have been found not to present the requisite elasticity to serve the purposes desired by me. Finally, it has been proposed to make the finger-hold of a soft-rubber sheath inclosing an undivided bulk of air between the rubber sheath and the penholder; but this construction has the disadvantage that the fingers of the user displace the air from the very point at which the fingers rest, thus practically permitting the fingers to come into contact with the rigid material of the penholder with nothing but a thin sheath of rubber between them.

Now I have found that I can construct a finger-hold comprising a sleeve of soft rubber

having a comparatively thin body and incasing a rigid and unyielding ferrule or core which nevertheless presents the necessary amount of elasticity and yield to the fingers of the writer. This I have accomplished by increasing the elasticity of the soft-rubber sleeve by means of tiny air-cells distributed through its mass. These air-cells may be regularly or irregularly distributed in the form of minute spherical or polyhedral air-holes, which as actually made by me are not over a fiftieth of an inch in diameter, or they may be more or less regularly distributed in the form of cylindrical or prismatic apertures running longitudinally or circumferentially part way or entirely through the body of the finger-hold. A finger-hold thus constructed has far greater elasticity than one built of solid soft rubber, since in my form the walls of soft rubber between the air-cells are comparatively thin and can be bent and stretched with the application of the minimum force, and this remains, too, in a measure even after the rubber has grown somewhat stiff with age.

In the drawings, Figure 1 shows a cross-section of a penholder and my finger-hold. Fig. 2 shows a longitudinal cross-section of a modified form of finger-hold. Fig. 3 is a section of Fig. 2 along the line 3 3. Fig. 4 is a longitudinal section of another modified form of finger-hold. Fig. 5 is a section of Fig. 4 along the line 5 5.

While my finger-hold may be applied to penholders of various constructions, I have shown, to fix ideas, a holder in the form of a stem A, having a tenon A', over which is slipped the metal core or ferrule B, having fastened in the outer end thereof the usual penholder-clip B'. The multicellular soft-rubber sleeve D is shown as surrounding and embracing the metal core or ferrule B. Manifestly, however, the material of the sleeve could be extended to cover the entire penholder.

The sleeve D in Fig. 1 is constructed of soft rubber having a very large number of tiny air-cells in the form of spheres or polyhedra irregularly distributed through its mass. As I have before remarked, the diameter of each of these little air-cells is preferably less than

one-fiftieth of an inch. Even though, then, the radial thickness of the cylindrical wall of the sleeve is not over an eighth or in extreme cases a quarter of an inch there will be quite a number of little air-pockets along any one of its radii.

In the form of sleeve shown on a large scale in Figs. 2 and 3 the air-cells are in the form of prisms or cylinders *d*, which may run either part way along or entirely through the finger-hold. These prismatic air-cells are somewhat regularly distributed, and their number is in practice even larger than I have indicated.

In the form of sleeve shown in Fig. 4 the air-cells are again prismatic rather than polyhedral in form; but instead of running longitudinally along the sleeve they run circumferentially around it at the same and at differing radial distances from the axis of the sleeve.

While I have referred to the material of the sleeve as "soft rubber," it is to be understood that I include by this term not merely pure soft

rubber, but also that form of soft rubber which pure soft rubber is mixed with terating or other compounds for the sake of greater cheapness or for imparting other desirable characteristics to the soft rubber.

I claim—

1. A penholder finger-hold comprising a rigid core for holding the pen and a surrounding soft-rubber sleeve having air-cells distributed throughout its mass, substantially as described.

2. A penholder finger-hold comprising a rigid tubular pen-holding ferrule and a surrounding soft-rubber sleeve having air-cells distributed throughout its mass, substantially as described.

In testimony whereof I have signed my name to this specification in the presence of two subscribing witnesses.

BYRON B. GOLDSMITH
